UNITED STATES PATENT OFFICE.

ALBERT P. ODELL, OF LIMA, OHIO; HELEN E. ODELL ADMINISTRATRIX OF SAID
ALBERT P. ODELL, DECEASED.

STORAGE-CASE.

1,106,236.

Specification of Letters Patent.

Patented Aug. 4, 1914.

Application filed March 25, 1911. Serial No. 616,869.

To all whom it may concern:

Be it known that I, ALBERT P. ODELL, a citizen of the United States, residing at Lima, in the county of Allen and State of Ohio, have invented new and useful Improvements in Storage-Cases, of which the following is a specification.

This invention relates to vacuum storage cases, and has for an object to provide a case designed for the reception of furs, woolens, or textiles which are liable to be attacked by moths.

In the drawing, forming a portion of this specification and in which like numerals of reference indicate similar parts in the several views:—Figure 1 is a perspective view of my improved case. Fig. 2 is a longitudinal section therethrough.

The case 1 comprises a receptacle 2 and an inner lining 3, the former being constructed of any suitable material and the latter being preferably constructed of sheet metal. The receptacle 2 is provided with an upper open end portion 4 in which is fitted a removable cover 5. This cover is provided with a reduced portion 6 which extends into the receptacle 2 and which yieldingly contacts with a rubber gasket 7, the latter being seated against the continuous shoulder 8 formed on the inner surfaces of the side and end walls of the receptacle at the opening 4. The inner lining 3 is preferably constructed from a seamless body so that in addition to the gasket 7 and closure 5 a perfect air tight storage space will be formed in the receptacle. The side and end walls of the receptacle have projecting therefrom studs 9 which are threaded at their outer ends and which extend through the cover 5, being removably engaged therewith and having fitted thereto clamping nuts 10 which may be brought to bear against the cover 5 so as to hold the reduced portion 6 thereof securely against the gasket 7. At one end, the case is formed to provide an opening 11 through which extends an exhaust nipple 12. At one end this nipple opens directly into the lining 3 of the case and at the opposite end the nipple opens directly into an exhaust or suction pump 13. The exhaust or suction pump conventionally

shown herein may be of any suitable well known construction which, when operated, will operate to expel the air from the storage space of the case. A suitable brace 55 bracket 14 is secured to the case and it embraces the casing of the pump, as shown. The pump herein illustrated is provided with a manually operated plunger 15 which, when drawn upwardly, will suck the air 60 from the said storage space of the case. The cover or any other suitable part of the case is provided with a carrying handle 16.

From the construction herein set forth and described it will be readily understood 65 that articles of apparel, such as furs or the like, when placed in the storage chamber of the case will be insured in the most efficient manner against damage by moths after the extraction of the air, as described. 70

I claim:—

A storage case comprising a bottom, four sides connected in upright relation to said bottom, a cover formed with a rabbeted portion extending along the four edges 75 thereof whereby a flange is formed, the four sides of said case being formed at their upper ends with a rabbeted portion whereby a continuous shoulder is formed spaced parallel and inwardly from the outer edges of 80 said sides, a lining secured in contact with the bottom and the inner surfaces of the sides of said case, said lining extending in a plane with said shoulders, a packing strip seating over said shoulders continuously, 85 said packing being spaced below the outer edges of said sides and overlying said lining, said cover arranged to be mounted over the outer edges of said sides, screw bolts screw threaded partially into the opposite sides of 90 said case, said screw bolts projecting above and passing through the flanges of said cover, said screw bolts being disposed laterally of said shoulder, and thumb nuts engaging the extremities of said screw bolts 95 to clamp said cover against said packing.

In testimony whereof I affix my signature in presence of two witnesses.

ALBERT P. ODELL.
